US0D1005985S

(12) **United States Design Patent** (10) **Patent No.:** **US D1,005,985 S**
(45) **Date of Patent:** **** Nov. 28, 2023**

(54) **LOUDSPEAKER**

(71) Applicant: **Harman International Industries, Incorporated**, Northridge, CA (US)

(72) Inventors: **Gianni Teruzzi**, Shenzhen (CN); **Ondrej Vaclavik**, Shenzhen (CN); **Alexander Demin**, Shenzhen (CN)

(73) Assignee: **Harman International Industries, Incorporated**, Northridge, CA (US)

(**) Term: **15 Years**

(21) Appl. No.: **29/719,321**

(22) Filed: **Jan. 2, 2020**

(51) **LOC (14) Cl.** **14-01**

(52) **U.S. Cl.**

USPC **D14/216**

(57) **CLAIM**

The ornamental design for a loudspeaker, as shown and described.

DESCRIPTION

FIG. 1 is a front perspective view of a loudspeaker showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top view thereof; and,

FIG. 7 is a bottom view thereof.

The broken lines in the figures form no part of the claimed design.

1 Claim, 7 Drawing Sheets
